UNITED STATES PATENT OFFICE.

JAMES BEARD SAMPLE, OF COLUMBUS, GEORGIA.

CAPSTAN.

SPECIFICATION forming part of Letters Patent No. 605,346, dated June 7, 1898.

Application filed January 27, 1898. Serial No. 668,154. (No model.)

To all whom it may concern:

Be it known that I, JAMES BEARD SAMPLE, a citizen of the United States, residing at Columbus, in the county of Muscogee and State 5 of Georgia, have invented certain new and useful Improvements in Capstans; and I do hereby declare the following to be a full, clear, and exact description of the invention, such as will enable others skilled in the art to which 10 it appertains to make and use the same.

This invention relates to an improvement in capstans; and it is embodied in the construction and arrangement of parts hereinafter described, and defined in the claims.

15 The aim and purpose of the invention is the provision of an improved machine designed for moving heavy bodies and machinery and for lifting and elevating purposes.

While I have shown in the accompanying 20 drawings an embodiment of the invention, I desire it understood that the same is shown for the purpose of explanation and not for limitation, as many changes can be made without departing from the nature and principle of the invention.

In the drawings like letters of reference 25 designate corresponding parts in both views.

Figure 1 is a top plan view of the machine. Fig. 2 is a side elevation showing parts in 30 section.

In the drawings, A represents the base of 35 the frame, on which is supported a step-box B.

C designates the side bars of the frame, which are conveniently placed, and D designates the top bar.

40 Loosely journaled in the step-box B is a vertical shaft E, extending up and having its upper end journaled in the bearing in the bar D. This shaft is provided on its lower end with a drum or pulley F of any convenient size or form. Fixedly secured to the vertical shaft and extending out therefrom in opposite directions are the sweeps or levers G, conveniently in pairs, diverging from the shaft.

45 The outer ends of each pair of these levers are united by a platform a, on which is mounted a motor K. These motors I have shown to be of the electric type; but I desire it understood that any convenient form of motor 50 can be employed.

Dependent from the platforms a are the

supporting-standards k, which are preferably constructed to serve as additional braces for the two members of the sweeps. In the lower ends of the standards are journaled the axles 55 of driving-wheels L, on the shafts of each of which are secured the sprocket-wheels l.

M is a driving-belt, conveniently of the link type, which connects the sprocket-wheel l with the sprocket-wheel l' on the motor-shaft. 60

N designates a circular track or way supported on posts n and located below the wheel L, and on which the latter travels. I have shown in the drawings this track as having a smooth surface; but I desire it understood 65 that the surface of the track may have projections thereon or be of the "rack" type and that the wheel may be made with its periphery to correspond.

O' designate the feed-wires, the same terminated in suitable brushes o, located at the center of the machine and conveniently below the upper bar. On the vertical shaft are secured the collector-rings o', with which the brushes engage, and from these rings the 75 wires are carried outward along the sweeps to the respective motors.

The gearing for the respective motors and driving-wheels is so fashioned and adjusted that a powerful leverage can be had and the 80 driving-wheels made to travel at a very rapid rate of speed.

In operation, a current of electricity being supplied to the motors, the driving-wheels are driven by the latter and rapidly travel 85 around the track. The power being applied to the outer ends of the sweeps will give an extended and very powerful leverage, and the rapidity with which the motors will drive the sweeps will be such that when a cable, belt, 90 or cord is attached to the pulley or drum it will be rapidly wound thereon, and owing to the long leverage very heavy bodies can be moved with but little trouble.

As above stated, I have shown my invention 95 in what may be considered its simplest form; but I desire it understood that the invention is not limited to the construction shown and described, as it is apparent that many minor changes can be made and other 100 types of motors used while still retaining the nature and principle of the invention.

Having thus described the invention, what I claim as new, and desire to secure by Letters Patent, is—

1. In a capstan, the combination with the 5 supporting-frame, of an upright shaft, sweeps connected to the shaft, a motor carried by the outer end of each of the sweeps, means for supplying the motors with motive power, drive-wheels driven by the motors and a track 10 on which the wheels move, substantially as described.

2. In a capstan, the combination with a 15 frame, of a vertical shaft loosely mounted therein, sweeps connected to the shaft and extending in opposite directions therefrom, platforms on the outer ends of the sweeps, a motor mounted on each of the platforms, a drive-wheel secured below each platform and having driving connections with the motor

thereon and a circular track on which the 20 drive-wheels move, substantially as described.

3. The combination with a frame, of a vertical shaft mounted therein, a sweep fixedly secured to the shaft and extending outwardly 25 therefrom, a motor on the outer end of the sweep, means for supplying the motor with motive power, a drive-wheel carried by the outer end of the sweep and having a gear connection with the motor, a circular track 30 on which the wheel moves and a drum on the shaft.

In testimony whereof I affix my signature in presence of two witnesses.

JAMES BEARD SAMPLE.
